UNITED STATES PATENT OFFICE.

WILLIAM F. MARKHAM, OF PLYMOUTH, MICHIGAN.

SPRING AIR-GUN.

SPECIFICATION forming part of Letters Patent No. 553,716, dated January 28, 1896.

Application filed September 24, 1895. Serial No. 563,496. (No model.)

To all whom it may concern:

Be it known that I, WILLIAM F. MARKHAM, a citizen of the United States, residing at Plymouth, in the county of Wayne and State 5 of Michigan, have invented certain new and useful Improvements in Spring Air-Guns, of which the following is a specification, reference being had therein to the accompanying drawings.

10 The invention consists in the construction of a spring air-gun, and particularly in the construction of what is known as a "break-down" gun—that is, one in which the spring is compressed by opening a hinge-joint between the barrel and stock or breaking down the stock upon said hinge-joint.

15 The invention in particular consists in the construction of the connecting parts on the barrel and stock, whereby the construction is simplified and cheapened and made more efficient than constructions heretofore in use, all as more fully hereinafter described.

20 In the drawings, Figure 1 is a sectional elevation of the butt of the barrel and front of the stock, showing the parts in breakdown 25 position. Fig. 2 is a cross-section on line $x-x$, the parts being in closed position. Fig. 3 is a detached perspective view of the locking plates at the front of the stock. Fig. 4 is a detached perspective view of one section of the 30 combined fore-arm, trigger-guard and pivot-arm.

25 A is an air-gun barrel, in which is the usual spring-actuated piston (not shown) for compressing the air behind the projectile. At the rear end is secured a combined fore-arm, trigger-guard and pivot-arm, which is of the following construction: Sheet-metal plates are struck into the shape shown in Fig. 4, 40 and two of these plates are riveted together, forming the trough-shaped fore-arm B, trigger-guard C and pivot-arm D. E is the trigger, pivoted on the cross-screw F and projecting below the fore-arm into the trigger-guard.

45 G is the gun-stock, at the forward end of which are secured the plates H, secured at their rear edges to the stock, projecting beyond the stock and having at their forward 50 edges the inwardly-extending flanges I.

These flanges near the top are preferably flared out, as shown at a, to form spring-jaws. The end of the arm D projects between these flanges I and is pivoted in the side pieces H by the bolt or screw J. On the sides of the 55 arm D are locking-lugs, preferably formed by striking out portions of the metal thereof, these lugs having the long inclined rear face b and the locking-shoulder or sharply-inclined front face c, as plainly shown in Fig. 2. 60

M is the connecting-rod from the stock to the spring-actuated piston, by means of which in breaking down the gun, as shown in Fig. 1, the spring is compressed, the piston engaging with the detent on the trigger; these parts 65 not being shown in detail, as they are a well-known construction.

When thus constructed, in order to compress the spring the operator breaks down the stock, as shown in Fig. 1, drawing back 70 the piston and engaging with the trigger-detent, as described. The parts are then turned to their normal position about the pivot J, and in this return movement the flanges a strike the long inclined faces b, opening the 75 spring-jaws until they reach the sharply-inclined locking-shoulder c, over which they spring and lock the parts together.

The plates H, I preferably form of a single piece of sheet metal bent into the shape shown 80 in Fig. 3, extending over the top of the stock and down on the sides thereof. The arm D, I preferably reinforce by means of a filling-block M', as shown in Fig. 2, to get the desired strength when made of sheet metal. 85

What I claim as my invention is—

1. In a breakdown gun, a combined fore-arm, trigger-guard and pivot-arm comprising two metal pieces formed substantially as described, a filling-block for the pivot-arm, and 90 means for securing the metal pieces together.

2. In a breakdown gun, the combination of the barrel, the stock, a rearward extension on the barrel formed of two separate metal pieces, forwardly-extending separated plates on the 95 stock between which the extension on the barrel is pivoted, locking-lugs on the extension struck up from the metal of the component pieces, and flanges on said plates adapted to engage the lugs, substantially as described. 100

3. In a breakdown air-gun, the combination of the stock, the barrel, a rearward downward extension on the barrel, forwardly-extending separated plates on the stock between which 5 the end of the extension or arm on the barrel extends and is pivoted, the flanges I on said plates, having the inclined portion *a* and the locking-lugs on the arm on the barrel, hav-

ing the long inclined portion *b* and the locking-shoulder *c* substantially as described. 10

In testimony whereof I affix my signature in presence of two witnesses.

WILLIAM F. MARKHAM.

Witnesses:

JAMES WHITTEMORE,
M. B. O'DOGHERTY.
